UNITED STATES PATENT OFFICE.

ROBERT N. FALGE AND WILBER M. JOHNSON, OF CLEVELAND, OHIO, ASSIGNORS TO
GENERAL ELECTRIC COMPANY, A CORPORATION OF NEW YORK.

LENS FOR VEHICLE LAMPS.

Application filed May 1, 1922. Serial No. 557,672.

To all whom it may concern:

Be it known that we, ROBERT N. FALGE and WILBER M. JOHNSON, both residing at Cleveland, county of Cuyahoga, State of Ohio, have invented certain new and useful Improvements in Lenses for Vehicle Lamps, of which the following is a specification.

Our invention relates to lenses for head-lamps of automobiles and other vehicles. 10 The object of our invention is to provide a lens which will furnish a desirable distribution of light without glare and which will, at the same time, dispense with the necessity for extreme accuracy of location of the light source.

The variation in position of the light source, ordinarily a concentrated incandescent lamp filament, which is ordinarily caused by inaccuracies in the manufacture 20 of the lamp or socket, has considerably less effect on the horizontal or approximately horizontal rays emitted from the reflector than it does on the other rays. When the lamp filament is located exactly at the focus 25 of the parabolic reflector, the rays will be all approximately horizontal. However, if the filament is displaced from the said focus, certain of the rays will be reflected in upward directions and others in downward directions. 30 According to our invention, the beam from the reflector is split up into zones, one of which comprises that portion of the beam in which all the rays are substantially horizontal or close to horizontal, and this is 35 made the dominant or uppermost beam. We also provide means for keeping the beams comprised in the other zones below or at least not higher than the dominant beam. Our invention, from one standpoint, requires 40 a lens divided into zones each of which is designed to properly refract the beam encountering it. Another feature of our invention has to do with the shape of the zones and, in fact, is of general application 45 where variation in refraction is required in the different portions of a lens.

In the drawing, which shows preferred forms, Figure 1 is a front elevation of a lens embodying our invention; Figure 2 is 50 the vertical section thereof on the line 2—2; Figure 3 is a horizontal section on the line 3—3; Figure 4 is a diagrammatic view showing the direction taken by certain light rays; Figure 5 is a diagrammatic view showing the 55 spot cast on the road by a headlamp com-

pising our invention, and Figure 6 is a front elevation of a modification.

Referring to the drawing, the lens 10 is provided with the usual clamping margin 11. The lens is divided into three zones. 60 The intermediate zone 12 is that which is encountered by the substantially horizontal rays, or rays making a small angle with the horizontal, reflected by the usual parabolic reflector. Unless the headlamp is tilted 65 downwardly, it is preferable to construct this central zone so that the light rays are bent slightly downward in order to ensure the avoidance of glare. The upper zone 13 and the lower zone 14 are prismatic and of 70 such refractive power that the beams directed thereby are inclined downwardly sufficiently so that no portion thereof is above the beam directed by the intermediate zone. As shown in Figures 4 and 5, this results 75 in these beams intersecting the roadway at points not further from the vehicle than the spot cast by the intermediate beam. The aforesaid zones 12, 13 and 14 are preferably provided with spreading prisms. Inasmuch 80 as the beams passing through the upper and lower zones 13 and 14 intersect the roadway at points closest to the vehicle, the refractive power of their spreading prisms is preferably made greater than those of zone 12. 85 The preferred form of our invention is shown diagrammatically in Figure 4 and the spots cast by the respective beams are shown in Figure 5. The spot 15 is cast by the beam directed by the lowermost zone, the 90 spot 16 by the beam directed by the uppermost zone, and the spot 17 by the beam directed by the intermediate zone. Inasmuch as the spot 15 is closest to the vehicle it is 95 preferably wider than the others, and to this end the refractive power of the vertical spreading prisms in the lowermost zone is of greater power than that of the corresponding prisms in the other zones.

The intermediate zone is preferably composed of two sectors, being wider at the periphery of the plate than at the center. The angles of spread are smaller from points at the periphery than from points nearer the center portion of the reflector. This 105 arises from the fact that such points are more distant from the filament making the intercepted angle from each of said points to the filament smaller and consequently causing the beam reflected from such point 110

- to be less divergent. The intermediate zone can therefore be made wider at the periphery of the lens than at the center as shown. More or less trouble is obviated, as shown 5 in Figure 1, by providing a non-transparent or translucent spot 18 at the center of the lens since the rays encountering this portion of the lens are most affected in their vertical displacement by variations in the 10 position of the light source or filament. As a modification, this portion of the intermediate zone may be made more highly refracting downwardly than the portions more remote from the center.
- 15 In Figure 6 we have shown a modification in which the sectors 19 are true mathematical sectors being bounded by radii of the lens circle. Such sector shaped zones may be adopted generally for uniformly refracting portions of a lens. However, we prefer, in order to have a factor of safety, 20 to make use of a construction similar to Figure 1.

What we claim as new and desire to secure by Letters Patent of the United States, 25 is:—

1. A lens for vehicle head lamps having focusing reflectors which comprises upper, lower and intermediate zones provided with

means for refracting downwardly light 30 transmitted therethrough from the reflector, all portions of said upper and lower zones being of higher refracting power than said intermediate zone and said intermediate zone being symmetrically disposed with 35 reference to the transverse axis of said lens and being wider at the periphery of said lens than at the center thereof.

2. A lens for vehicle head lamps having focusing reflectors which comprises upper, 40 lower and intermediate zones provided with means for refracting downwardly light transmitted therethrough from the reflector, all portions of said upper and lower zones being of higher refracting power than 45 said intermediate zone, said intermediate zone being symmetrically disposed with reference to the transverse axis of said lens and being wider at the periphery of said lens than at the center thereof, and said lens being provided with vertical ribs for spreading the light laterally, the ribs covering said intermediate zone being of the least spreading power.

In witness whereof, we have hereunto set 55 our hands this 27 day of April 1922.

ROBERT N. FALGE.
WILBER M. JOHNSON.
